UNITED STATES PATENT OFFICE

WILLIAM TALBOT TRUITT, OF NEW YORK, N. Y.

HAT-HOLDER.

939,352.

Specification of Letters Patent.

Patented Nov. 9, 1909.

Application filed November 21, 1908. Serial No. 463,920.

To all whom it may concern:

Be it known that I, WILLIAM T. TRUITT, a citizen of the United States, residing at New York city, in the county of New York and State of New York, have invented certain new and useful Improvements in Hat-Holders, of which the following is a specification.

This invention relates to the subject of store furniture, and more particularly to those types of display fixtures utilized particularly as hat holders for the display of millinery.

To this end the invention particularly relates to a hat holder especially designed for holding women's hats for display purposes, and one of the principal objects of the invention is to provide a holder that will have a firm engagement with its support, yet may be readily adjusted thereon or removed therefrom, and which may be readily shaped to permit of the hats being viewed at different angles.

In carrying out the objects of the invention generally stated above, it will, of course, be understood that the essential features thereof are susceptible of structural changes, certain preferred and practical embodiments of which are shown in the accompanying drawings, wherein:

Figure 1 is a perspective view of two hat holders showing the same in engagement with their support, one of said holders being bent a different angle from the other. Fig. 2 is a transverse sectional view taken on the line 2—2, Fig. 1 showing the engagement between the hat holder and its support. Fig. 3 is a detail perspective view of a slightly modified form of hat holder.

Like references designate corresponding parts in the several figures of the drawings.

Referring to the embodiment of the invention suggested in Figs. 1 and 2 of the drawings, the numeral 1 designates the supporting element which is preferably in the form of a strip of molding adapted to be secured in any place where it is desired to display the hat or hats, and of any desired length according to the number of hangers adapted to be adjustably fitted thereto. Hence, it will be understood that the said supporting element or strip may be fitted either in a hat box or utilized as a piece of store furniture either in the show windows or in the store proper for displaying millinery.

In carrying out the invention, the supporting element may be supported in place in any approved manner and may be used either vertically, horizontally, or at an angle, and for illustrative purposes there is suggested in Fig. 1 of the drawings the use of a supporting strip of molding 1 adapted to be arranged vertically and supporting one or more of the improved hat hangers which are adjustable longitudinally of the said support. As shown, the strip of molding 1 constituting the supporting element is preferably formed in opposite side edges thereof with the longitudinally arranged side retaining grooves 2 producing, at the front side of the strip, the oppositely arranged longitudinal holding ribs 3 cooperating with the individual holders in the manner to be presently explained.

In the manufacture of the individual hat holders, the same may be made in various ways without departing from the invention, though in all of the preferable forms of the invention, it is the intention to construct the individual holders of wire bent to provide the working elements of the holder. One or more lengths of wire may be thus utilized in connection with the individual holders, but for illustrative purposes there are shown in the drawings certain forms of construction which exemplify the special features which are claimed herein.

Referring in the first place to that form of the invention shown in Figs. 1 and 2 of the drawings, it will be observed that each individual hat holder essentially consists of an offstanding wire bracket member designated in its entirety by the reference numeral 4, and which bracket member carries all of the working parts of the holder. The said bracket member includes in its construction a main outstanding hanger arm 5 provided at the outer extremity thereof with an up-turned supporting post 6, from the upper extremity of which post is bent outwardly therefrom a crown engaging clasp 7. This crown engaging clasp 7 is in the form of a split ring embodying the opposite duplicate bowed clasp jaws 8, each of which is provided at the front end thereof with a down-turned finger or hand piece 9. By reason of what has been termed the split form of the crown engaging clasp 7, and the fact that the wire constituting the same is a suitable grade of spring wire, it will be understood that by grasping the downturned finger or

hand pieces 9 of the opposite clasp jaws 8, the latter may be drawn together so as to admit of the crown of the hat being placed thereover, after which pressure upon the 5 finger or hand piece is released, thereby permitting the jaws to spring outwardly into clasping engagement with the hat crown with the result of holding the hat firmly in the desired display position.

10 The offstanding post 6 of the bracket member may be either vertically arranged or disposed at any other desired angle according to the angle at which it may be intended to display the hat, and in order to 15 give the preferred inclination to the crown engaging clasp 7, it is only necessary to deflect the outer end portion of the hanger arm 5 either up or down as indicated at the point 10 on the hat hanger shown in the 20 lower part of Fig. 1 of the drawings. The main outstanding hanger arm 5 of the bracket member 4 also includes in its construction an inclined bracing leg 11 having a connection 12 at its upper end with an 25 intermediate part of the hanger arm 5 and whose lower end is readily united to or formed with a lower slide clasp 13 which may be conveniently formed by bending the wire into an approximate C-shape to produce 30 the oppositely arranged inturned clasping hooks or clamps 14 which frictionally and slidably embrace the opposite holding ribs 3 of the supporting element. An upper slide clasp 15, similar to the lower slide 35 clasp 13 is provided at the inner end of the hanger arm 5 and also includes opposite inturned spring clasping hooks or clamps 16 which frictionally and slidably embrace the holding ribs 3.

40 The upper and lower sets of clasping hooks or clamps 16 and 14 are preferably braced and connected by intermediate brace spring bars 17 lying in the retaining grooves 2 of the supporting element, thus providing 45 a very rigid and firm structure which admits of the individual hat hangers being slid up and down on the supporting element to any desired position, and held in the latter through the frictional engagement of the 50 slide clasps with the holding ribs 3.

As suggested in Figs. 1 and 2 of the drawings, the individual hat hangers may be conveniently formed of two lengths of wire each of which is bent to form one half of the 55 hanger as above described, and is an exact duplicate of the other half, the two lengths of wire being banded, soldered, or otherwise rigidly united at fastening points 18. However, the entire hat hanger may be formed of 60 a single length of wire, as suggested in Fig. 3 of the drawings, and the latter figure of the drawings also illustrates another em-

bodiment of the invention, viz: that of having the supporting element 1 arranged horizontally and hence necessitating arranging 65 the upper and lower slide clasps of the bracket member horizontally instead of vertically. In this adaptation of the invention, it will be observed by reference to Fig. 3 of the drawings that the hanger arm 5 is 70 formed at its inner end with a horizontal slide clasp 15^a embodying the inturned clasping hooks or clamps 16^a slidably embracing the holding ribs of the supporting element, while the bracing leg 11 is likewise formed 75 with a lower slide clasp 13^a having the in-turned spring clasping hooks or clamps 14^a, and the latter connected with the corresponding upper hooks or clamps 16^a by intermediate brace bars 17^a, the latter, however, lying 80 on the outside of the face of the supporting element and disposed vertically. In other respects, the essential features shown in Fig. 3 are the same as the construction illustrated in Figs. 1 and 2.

85 From the foregoing it will be understood that various changes in the form, proportion, and minor details of construction may be resorted to without departing from the spirit or sacrificing any of the advantages of 90 the invention.

I claim:

1. In a hat holder of the class described, the combination with a supporting element, of the holder proper comprising a main 95 hanger arm provided at its outer end with an offstanding hat support and at its inner end provided with a slide clasp slidably engaging such supporting element, a brace connected with the hanger arm and also provided with a slide clasp slidably engaging said supporting element, and connectors between the separate slide clasps.

2. In a hat holder of the class described, the combination with a supporting element 105 having oppositely arranged holding ribs of the holder proper comprising a wire bracket member having a main hanger arm provided at its outer extremity with a supporting post carrying a hat support, and at its inner end provided with a slide clasp having clasping hooks engaging said holding ribs, an inclined brace leg united at its upper end with a hanger arm and provided at its lower end with a slide clasp having clasping hooks 110 embracing said holding ribs, and connecting bars between the upper and lower holding hooks or clamps.

115 In testimony whereof I hereunto affix my signature in the presence of two witnesses.

120 WM. TALBOT TRUITT.
